LOCOMOTIVE CONTROL

Original Filed May 25, 1925 2 Sheets-Sheet 2

Fig. 2

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

LOCOMOTIVE CONTROL.

Application filed May 25, 1925, Serial No. 32,543. Renewed May 31, 1927.

My invention relates to control systems, and has for its principal object the provision of an improved system for controlling the power interchanged between an alternating current system and the motive apparatus of an electric locomotive both while motoring and during regeneration.

Various arrangements have been proposed and used in the past for controlling the power interchanged between a power system and the motive apparatus of an electric locomotive. In the operation of these arrangements, it is customary to vary the electrical conditions of the motive apparatus by means of switching devices, the contacts of which are likely to deteriorate due to the arcing and mechanical wear incident to their engagement and disengagement. In accordance with my invention, this difficulty is obviated and smooth acceleration and deceleration of the motive apparatus are effected by variation in the grid potential of an electron discharge device interposed between the power system and locomotive.

My invention will be better understood from the following description when considered in connection with the accompanying drawing and its scope will be pointed out in the appended claims.

Referring to the drawing, Fig. 1 shows a system wherein my invention has been embodied; and Fig. 2 shows a similar system comprising a modified form of electron discharge device for controlling the power interchanged between the power system and motive apparatus.

Fig. 1 shows a plurality of electric machines 1, 2, 3 and 4 arranged to have their respective armature circuits 5, 6, 7 and 8 interconnected with a power system, shown as a trolley line 9, through means comprising a contact device 10, transformer 11, an electron discharge device shown as a mercury rectifier 12, reactor 13 which is provided for the purpose of smoothing out current pulsations in the armature circuits, and reversing switch 14 which is adapted to reverse the connections of the two groups of armature circuits, to the vapor electric device 12. The field circuits 15, 16, 17 and 18 of the machines 1, 2, 3 and 4 respectively are connected to the line 9, through reactor 19, electron discharge device 20 and transformer 21, the primary circuit of this transformer being shown as connected in series with the primary circuit of the main transformer 11 and therefore in series relation with the electron discharge device 12, and a switch 22 being provided for connecting the primary circuit of the transformer 21 across a part of the primary circuit of the main transformer 11 or in shunt relation to the device 12 during regeneration. The machine field and armature circuits are thus connected in series relation during motoring and in shunt relation during regeneration. A switch 23 and source of current 24 are provided for initiating operation of the device 20.

It will be observed that a switch 25 and source of current 26 are provided for initiating operation of the device 12; that anodes 27 to 30 of this device are connected to the terminals of secondary circuits 31 and 32 of the main transformer 11; that the midpoints of these secondary circuits are connected to the cathode 30' of device 12 through switch 14, armature windings 7 and 8 and armature windings 5 and 6 respectively, and reactor 13; and that grids 33 to 36 of device 12 are connected through current limiting resistors 37 to 40 and a transformer 41 to a phase control device of well known form which comprises a polyphase stator winding 43 and a single phase winding 44, mounted on a rotor core 45. The stator winding 43 is connected to the line 9 through contact device 10 and to ground through reactor 46 and condenser 47 which are provided for producing a rotating field in the core member of the phase shifting device. It will be apparent that any other suitable means of producing a rotating field in the core members of the phase control device may be utilized.

Condensers 48 and 49 are connected to the terminals of the secondary circuits 31 and 32 respectively in order to ensure stable operation of the electron discharge device 12 during slight interruptions of the circuit between the line 9 and contact device 10. A control lever 50 is mounted on the shaft of the phase control device 42 to facilitate variation in the potential of the grids 33, 34, 35 and 36.

Assuming the control lever 50 to be in a position to cause opposed voltages to be impressed on the grid and anode circuits of the device 12, switch 22 to be open, switch 14 to

be closed in its right hand position and operation of the devices 12 and 20 to have been initiated by means of switches 23 and 25, it will be readily understood that the field 5 windings 15 to 18 will be excited but no current will be transmitted to the armature circuits 5 to 8 for the reason that the grid voltages of device 12 are opposed to the anode voltages of this device. The machines 10 1 to 4 will therefore be stationary.

In order to accelerate the machines, the lever 50 is operated in a manner to decrease the phase difference between the grid and anode voltages, thus gradually raising the 15 voltage at which current is transmitted through device 12 and lengthening the period of current transmission until current is continuously transmitted at a voltage substantially equal to the secondary voltage of transformer 11 when the grid and anode voltages are in phase. It will be apparent that other suitable means, such as an adjustable source of unidirectional voltage, for example, may be utilized to bias the grid potential and 20 vary the voltage at which transmission of current to and from the machines 1 to 4 is effected.

The machines 1 to 4 are decelerated by 25 operating the lever 50 in a manner to increase the phase difference between anode and grid voltages of device 12, the circuit through this device being interrupted when these voltages are brought into phase opposition.

If it is desired to cause the machines 1 to 4 to supply power to the line 9 while driven by the momentum of the locomotive, the switch 14 is operated in a manner to reverse the connections between the armature 30 circuits 5 to 8 and device 12, the switch 22 is closed and the lever 50 is operated as before to decrease the phase difference between the anode and grid voltages of device 12. The switch 22 thus makes it possible to operate 35 the machines 1 to 4 with series characteristics while motoring and with shunt characteristics while regenerating. This method of operation is of advantage in that considerable fluctuations in load are likely to 40 occur during regeneration.

Fig. 2 shows a system which differs from that just described in that the field and armature currents of machines 1 to 4 are rectified by a single device 12' provided with field anodes 51 and 52 which may be utilized 45 both to rectify the machine field currents and to excite the device 12' in cases where the field circuits are energized continuously. The use of the separate secondary circuits 50 31 and 32 is of advantage in that their leakage reactance tends to produce a proper division of load between the two groups of motors.

The embodiments of the invention illustrated and described herein have been se- 55

lected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States, is:

1. The combination of an electric machine comprising field and armature circuits, a power line, an electron discharge device connected between said machine and line and provided with grids for controlling the voltage at which current is transmitted to and from said machine, means for varying the grid potential of said device, field control means connected to said line in series relation with said device, and means for connecting said field control means in shunt relation to said device while said machine is operated to supply current to said line.

2. The combination of an electric machine comprising field and armature circuits, a power line, an electron discharge device connected between said machine and line and provided with grids for controlling the voltage at which current is transmitted to and from said machine, phase control means connected to said grid for varying the phase of the voltage applied thereto, field control means arranged to be connected to said line in series relation with said device while said machine is motoring, and means for connecting said field control means to said line in shunt relation to said device while said machine is generating.

3. The combination of a power circuit, an electric locomotive comprising motive apparatus having field and armature circuits, a vapor electric device connected between said line and said armature circuit and provided with grids for controlling the voltage at which current is transmitted to and from said armature circuit, field control means arranged to be connected to said power circuit in series relation with said device for controlling the energization of said field circuit while said locomotive is driven by said apparatus, and means for connecting said field control means to said line in shunt relation with said device while said apparatus is driven by the momentum of said locomotive.

4. The method of operating an electric locomotive comprising motive apparatus having field and armature circuits connected to a power circuit through an electron discharge device provided with anodes and grids for controlling the voltage at which current is transmitted to and from said apparatus, which consists in connecting said field circuit to said power circuit in series relation with said device, decreasing the

phase difference between the potentials of said anodes and grids to accelerate said apparatus, increasing said phase difference to decelerate said apparatus and interrupt the circuit between said armature and power circuits, connecting said field circuit to said power circuit in shunt relation to said device while said apparatus is driven by the momentum of said locomotive, and varying 10 said phase difference to control the speed at which said apparatus is driven by the momentum of said locomotive.

5. The combination of an electric machine comprising field and armature circuits, a power line, an electron discharge device connected between said machine and line and provided with grids for controlling the voltage at which current is transmitted to and from said machine, means for varying 15 the grid potential of said device, field control means connected to said line in series relation with said device, means for connecting said field control means in shunt relation to said device while said machine is operated 20 to supply current to said line, and means for maintaining the operation of said device during momentary interruptions in the connection between said line and said device.

6. The combination of an electric machine comprising field and armature circuits, a power line, an electron discharge device connected between said machine and line and provided with grids for controlling the voltage at which current is transmitted to and 25 from said machine, means for varying the grid potential of said device, field control means connected to said line in series relation with said device, means for connecting said field control means in shunt relation to 30 said device while said machine is operated to supply current to said line, and condens- 35 ance means connected to said line in shunt to said device for maintaining the opera- 40 tion of said device during momentary in-

terruptions in the connection between said line and said device.

7. The combination of a power line, a transformer comprising a primary circuit connected to said line and a plurality of secondary circuits inductively related to said primary circuit, a plurality of groups of electric machines, and an electron discharge device arranged to connect each of said groups to a different one of said secondary 50 circuits and provided with grids for controlling the voltage at which current is transmitted between said groups and said secondary circuits.

8. The combination of a power line, a transformer comprising a primary circuit 60 connected to said line and a plurality of secondary circuits inductively related to said primary circuit, a plurality of electric machines, and an electron discharge device provided with grids for controlling the voltage 65 at which current is transmitted between said machines and said secondary circuits and arranged to connect some of said machines to one of said secondary circuits and other of said machines to other of said secondary 70 circuits.

9. The combination of a power line, a transformer comprising a primary circuit connected to said line and a plurality of secondary circuits inductively related to said 75 primary circuit, a plurality of electric machines, electron discharge means provided with grids for controlling the voltage at which current is transmitted between said machines and said secondary circuits and 80 arranged to connect some of said machines to one of said secondary circuits and other of said machines to other of said secondary circuits, and phase control means for varying 85 the potential of said grids.

In witness whereof, I have hereunto set my hand this 23d day of May 1925.

ERNST F. W. ALEXANDERSON.
